T. H. LLOYD.
CHASER ADJUSTING TOOL.
APPLICATION FILED JUNE 7, 1921.

1,415,182.

Patented May 9, 1922.

UNITED STATES PATENT OFFICE.

THOMAS H. LLOYD, OF SPRINGFIELD, MASSACHUSETTS, ASSIGNOR TO WYCKOFF & LLOYD COMPANY, OF SPRINGFIELD, MASSACHUSETTS, A CORPORATION OF MASSACHUSETTS.

CHASER-ADJUSTING TOOL.

1,415,182.

Specification of Letters Patent. Patented May 9, 1922.

Application filed June 7, 1921. Serial No. 475,626.

To all whom it may concern:

Be it known that I, THOMAS H. LLOYD, a citizen of the United States of America, residing at Springfield, in the county of 5 Hampden and Commonwealth of Massachusetts, have invented certain new and useful Improvements in Chaser-Adjusting Tools, of which the following is a specification.

10 This invention relates to improvements in chaser adjusting implements for use in adjusting or setting the chasers, or lands, in thread cutting dies which are used by plumbers and steam fitters for cutting the 15 threads on the ends of pipes.

In practice, it has been found a slow and difficult matter to accurately adjust all of the chasers in a thread cutting die so that in operation the teeth of each chaser will perform its proper share of the work; or in other words, the teeth of one chaser will not cut a thread that is deeper than those cut by the other chasers. In order to have each chaser perform its individual share of the 20 work, they must all be accurately set, or adjusted, with relation to the forward surface 25 of the chaser holder.

An object, therefore, of the present invention, is to provide a tool, or implement, 30 which may be employed to quickly and accurately adjust the chasers of a thread cutting die so that they will equally perform their individual share of the work.

Broadly considered, the implement comprises a base-piece or member that is designed to rest against the chaser holder, and a member pivotally attached to the base-piece with which the ends of the cutting threads of the chasers engage, whereby, 35 when the chasers are correctly adjusted, the pointer which is carried by the pivoted member, will register or be in line with its zero position. The zero position is indicated on the base-piece. The implement will 40 be fully described in the body of the specification, and its novelty will be particularly pointed out in the claims.

Referring to the drawings:

Fig. 1 is a plan view of a portion of the 50 die in which the chasers are placed, and shows a chaser holder, one of the chasers, the thread for adjusting the same, and also the implement in use for determining the position of the chaser.

Fig. 2 is a detail side view of the implement with the pointer in its zero position.

Fig. 2^A is an end view of Fig. 2.

Fig. 3 is a modification in which a coil of insulated wire is wound about a portion of the base piece of the implement for magnetically retaining it in place on the chaser holder.

Fig. 4 is a view showing the implement in use and magnetized to prevent its detachment.

Fig. 5 is a view illustrating the relation of the chasers to the pipe on which a thread is to be cut.

Referring to the drawings in detail: 1 designates one of the chaser holders, 2 one 70 of the chasers thereon, 3 a threaded member having a squared end 4 for receiving a suitable tool for turning the threaded member for moving and adjusting the chaser on its holder.

The implement herein shown is employed in order to accurately position the chaser 2 with reference to the surfaces 5 and 6 of the holder so that the forward ends 7 of the teeth of the chaser will lie in the same plane 80 as the surfaces 5 and 6 and also in or tangent to the circle 8 which indicates a section of the pipe on which a thread is to be cut. The implement comprises the base-piece 9 having the member 10 pivotally secured thereto by means of the pin 11. The piece 9 and member 10 have curved surfaces which fit together as indicated at 12. 13 indicates a lip which extends outward from the base-piece 9 and is for engaging the side 90 of the chaser holder, as shown, to prevent the implement from moving out of place when in use. Attached to the pivotally connected piece 10 is a pointer 14. This pointer will register with the line 15 when the piece 9 and member 10 are in the same plane, as shown in Figs. 2 and 3. The implement is used as follows:

The base piece 9 is placed on or against the surfaces 5 and 6 of the chaser holder 1, 100 the piece 10 is placed against the ends 7 of the teeth of the chaser 2, the operator then rotates the screw 3 by applying a suitable tool to the part 4. This operation causes the chaser to move forward and turn the 105 pivotal part 10 and pointer 14. When the pointer registers with the line 15 the forward ends of the teeth of the chaser 2 will

be in the same plane as the surfaces 5 and 6. They will also be an equal radial distance from the center of the pipe, indicated in Fig. 5 at 8.

- 5 For the purpose of retaining the implement in place on the chaser holder 1, several turns of insulated magnet wire are wound around a recessed part 9' of the base-piece 9, as indicated at 16. A suitable 10 source of electrical energy 17 and electric circuit 18 is connected to the coil 16 with a circuit closer key 19 therein. When the circuit is closed the base-piece 9 becomes magnetized and will remain on the surfaces 5 15 and 6 of the holder 1 as long as the circuit remains closed, thus preventing the implement from becoming detached during the adjusting operation of the chasers. As shown in Fig. 4, the implement would fall 20 by gravity unless it was held in place by some suitable means. I have therefore made use of the electric current for magnetizing the implement, as being convenient and suitable for this purpose, as is readily understood.

25 20 designates the end portion of the lip or flange 13 which engages the inclined surface 1' of the holder 1 adjacent the surface 5 for the purpose of accurately locating the 30 implement on the surfaces 5 and 6 and longitudinally of the implement. The lip 13 and its end part 20 Fig. 1 therefore permits both longitudinal and lateral adjustment of the implement.

35 What I claim is:

1. An implement for the purpose described, comprising a base-piece, a part 40 movably connected thereto, a pointer or indicating member carried by the movable part, the base piece having a lip for positioning the base piece on a fixed reference surface, said base-piece being designed for engagement with the fixed reference surface and the movable part with a part that 45 is to be adjusted into the same plane as the reference surface.

50 2. In an implement for adjusting the chasers of a thread cutting die, a base-piece for engaging the chaser holder, a part pivotally connected to the base piece and carrying a pointer which is designed to register with an indicating line on the base-piece when the forward cutting teeth of a chaser are in the same plane as the surface on 55 which the base-piece rests, as described.

3. An implement for the purpose described, comprising a base-piece provided with a reference line, a part movably connected to the base-piece, a pointer on the 60 movable part and designed to register with the reference line when the base-piece and

movable part are in the same plane, as described.

4. A chaser adjusting implement comprising a base-piece having a flange part 65 for positioning the same on the chaser both longitudinally and transversely thereof, and a part movably connected to the base piece and means for determining when the base-piece and movable part are in alignment, as 70 described.

5. A chaser adjusting implement comprising a base-piece having a flange part for positioning the same on the chaser both longitudinally and transversely thereof, a 75 part movably connected to the base piece, means for determining when the faces of base-piece and the movable part are in the same plane, as described, and means for temporarily retaining the implement in place 80 on the holder.

6. A chaser adjusting implement comprising a base-piece or the like, having a coil of magnet wire thereon, a part movably connected to said piece, a pointer device on the 85 movable piece and movable with relation to the base piece for determining its position with reference to said piece, and said implement being magnetically held in place when the circuit is closed through the coil, 90 as described.

7. A chaser adjusting implement comprising a base-piece or the like, having a coil of magnet wire thereon, a part movably connected to said piece, a pointer device on the movable piece and movable with 95 relation to the base piece for determining its position with reference to said piece, said implement being magnetically held in place when the circuit is closed through the coil, 100 as described, and means on the base-piece for determining the position of the implement when in use, both as to its lateral and longitudinal position.

8. A device for determining the correct 105 radial adjustment of a chaser of a thread cutting die, comprising in combination, of a base or reference piece for engaging a face of the die-holder and beyond which the cutting point of the chaser extends, a member 110 movably connected to the base-piece with which the cutting point of the chaser engages, a pointer fixedly secured to the movable member and arranged to swing over the base-piece with reference to a zero point 115 thereon for indicating when the cutting point of the chaser is in the same plane as the face of the die holder and with which face the base-piece of the device engages, as described.

THOMAS H. LLOYD.
